UNITED STATES PATENT OFFICE.

HAROLD ROWNTREE, OF KENILWORTH, ILLINOIS, ASSIGNOR TO NATIONAL PNEUMATIC COMPANY, OF NEW YORK, N. Y., A CORPORATION OF WEST VIRGINIA.

COMBINED DOOR AND STEP-COVER OPERATING MECHANISM FOR PASSENGER-CARS.

1,184,133.

Specification of Letters Patent.

Patented May 23, 1916.

Application filed October 29, 1912. Serial No. 728,377.

To all whom it may concern:

Be it known that I, HAROLD ROWNTREE, a citizen of the United States, residing at Kenilworth, county of Cook, State of Illinois, have made a certain new and useful Invention in combined Door and Step-Cover Operating Mechanism for Passenger-Cars, of which the following is a specification.

10 This invention relates to a combined door and step cover operating mechanism for passenger cars.

The object of the invention is to provide a combined door and step cover operating mechanism which is simple in construction and efficient in operation.

A further object is to provide a construction of the character referred to which is automatic in action.

20 A further object is to provide a mechanism of the character referred to wherein, in opening, the step cover is moved into position collapsed against the door before the door movement begins.

25 A further object is to provide a mechanism of the character referred to wherein, in closing, the door completes its closing movement before the step cover is moved into position to accomplish its function of 30 cover for the steps.

Other objects of the invention will appear more fully hereinafter.

The invention consists substantially in the construction, combination, location and arrangement of parts, all as will be more fully hereinafter set forth, as shown in the accompanying drawings and finally pointed out in the appended claims.

Referring to the accompanying drawings, 40 and to the various views and reference signs appearing thereon:—Figure 1 is a view in elevation of a door showing operation of a mechanism embodying the principles of my invention, the door being in closed position. Fig. 2 is a view in side elevation, showing the parts with the door in its closed position and the step cover in its normal position when the door is closed.

Fig. 3 is a broken view in perspective of a 50 door showing a step cover applied thereto in accordance with my invention. Fig. 4 is a view in horizontal section on the line 4, 4, Fig. 3, looking in the direction of the arrows. Fig. 5 is a similar view on the line 5, 5, Fig.

55 3, looking in the direction of the arrows.

Fig. 6 is a broken detail view in section on the line 6, 6, Fig. 4, looking in the direction of the arrows.

The same part is designated by the same reference numeral wherever it occurs 60 throughout the several views.

In passenger cars, more particularly of the interurban type, the steps are entirely or largely inside the car line. The doors generally slide into pockets in the side of the 65 car, and when the doors are in a closed position there is a considerable portion of the steps inside the door, leaving an exposed area or opening which is exceedingly dangerous to passengers and liable to cause accidents.

Ordinarily there is provided a manually operated flap or step cover for this aperture which is raised and lowered by hand in some proposed arrangements, or which is 70 carried by the door at an angle therewith and moves with the door into the side pocket of the car. This is objectionable as in the case of interurban cars which have to make frequent stops, the cover must be raised 75 and lowered by hand at each stop, thereby causing delay in the rapid transit of the car, and when the cover is carried by the door an enlarged pocket is necessary, and besides in practice such an arrangement has 80 not been found to be satisfactory.

It is among the special purposes of my present invention to provide means whereby the opening and closing of the door and the raising and lowering of the step cover is 90 accomplished automatically. I also propose to construct and arrange the step cover and its operating mechanism so that there will be no possibility of passengers standing upon it at the moment the door is opened, and also so that, in closing, the door will 95 complete its closing movement before the step cover is projected into position to form a cover for the step area to be guarded, and in opening the cover will close against the side of the door before the opening movement of the door commences.

In carrying out my invention, I propose to provide a shield or step cover attached to the door, which when the door is closed will project from the door toward the interior of the platform at an angle and in such relation as to cover the steps, and when the door is open will lie up against the side of the door. And I provide means whereby when 100 105 110

the door is operated or moved to open the door the shield or step cover is first drawn flat against the door before the door begins its opening movement, and in closing, the 5 door completes its closing movement and then the shield or cover is projected into position over the steps to close the exposed step opening in the platform.

While I have shown a specific construction 10 and arrangement embodying the principles of my invention, I do not wish to be limited or restricted to the exact details shown and now to be described.

Any suitable or convenient construction 15 of operating mechanism may be employed. In the form shown a pneumatic motor mechanism is used consisting of a double ended power cylinder 1, in which operates a double piston connected by an intermediate rack, 20 not shown, which engages with a segment gear 2, to which is secured a lever 3. Such an operating motor is shown in Patent No. 1,001,989, issued Aug. 29, 1911. The free end of this lever is pivotally connected, as 25 at 4, to a slide 5, which operates on the slide bar 6, fastened to the rear edge of the door 12, at 7 and 8. The object of the mechanism thus far described is to open and close the door, which result is accomplished by the 30 movement of the piston in the cylinder and the consequent rocking of the segment and the lever 3. When the lever 3 raises along the slide bar 6 the door is drawn open and when said lever is lowered along the said 35 bar the door is moved toward its closed position.

The gear 2, is fastened solidly upon the pin or shaft 9. A cam 10 is also fastened upon the said pin or shaft 9 to rock therewith. This cam has a concentric circular portion for the greater portion of its periphery but is provided with a flattened face 11, on one portion of its peripheral edge. A lever 21 is pivoted at 23 to a suitable fixed 45 support in such a position that the edge of said lever rests against the flat face 11 of the cam 10, when the door is in fully closed position. The outer or free end of lever 21 has fixed thereon an arm 22. The door 12 carries two vertical slide rods 13, and 14, 50 on its inside face near its front and rear edges respectively, and on these slide rods the upper edge of a step cover or shield 15, is pivotally connected so that the upper edge 55 of the cover can slide upward and downward on the slides 13 and 14. These slides are arranged so that when the cover or shield is in its highest upper position on the slides, the cover or shield 15 lies folded 60 flat against the door, and when the cover 15 is in its lowest position on the slides 13 and 14, the lower edge of the cover 15 will be projected sufficiently outwardly to cover the step aperture.

65 On the inner face of the door at or near

its front and rear edges are fastened bearings 16 and 17, in which a shaft 18 is journaled. This shaft carries two projecting arms 19, the outer ends of which are pivotally connected to cover 15 as shown, and said arms or the hubs thereof, take bearing against the bearing 16, 17, thereby preventing the shaft 18 from endwise or longitudinal movement relatively to the door 12, that is, the shaft 18 is carried by and moves with 75 the door in its motion in opening and closing.

When the shaft 18 is partially revolved in its bearings so as to rock the arm 19 upwardly, it will be seen that the step cover 80 or shield 15 will be moved upwardly on its guides 13, 14, and its lower edge will be moved inwardly, so as to lie flat against the door, and when the arms 19, are rocked downwardly, the cover 15 will be moved 85 downwardly on its guides 13, 14, and its lower edge projected outwardly from the door toward the interior of the platform and into position to cover the step aperture.

Many specifically different constructions 90 may be provided for rocking the shaft 18 in the timely operation thereof, and in accordance with my invention the operation of said shaft should be so related to the door movement as to cause the step cover to 95 be moved into position to lie against the door before the door commences its movement in opening, and to remain against the door till the door completes its closing movement before it is projected into position to 100 form a step cover. In the arrangement shown for accomplishing this result the shaft 18 projects beyond the rear edge of the door 12, a somewhat greater distance than the travel of said door, and at or near its rear end, said shaft passes freely through an arm or lever 20. This arm 20 is so mounted 105 as to rock only in an upward and downward direction and the shaft 18 slides through it during the opening and closing movements 110 of the door.

Means are provided whereby any rocking movement given to the lever 20, is transmitted to the shaft 18. This is accomplished by making the shaft 18, or that portion of it, that slides through the lever 20, of square cross section, and by making the bore of the hub of arm 20, through 115 which it slides, of similar shape.

The outer or free end of lever 21, is connected by a crank arm or rod 22, to the outer end of lever 20. The rotation of the cam 10, causes the lever 21 to be rocked vertically and by reason of the free end of said lever being removed farther from the fulcrum 23 than cam 10, and by reason of the lever 21 lying against the flattened surface of the cam, when the door is completely closed, the action of the cam upon the lever 21, is magnified at the initial stage of rota- 120 125 130

tion of the cam, thereby giving a quick and rapid motion to said lever and through it and the connecting rod 22 to the arm or lever 20 thereby rocking shaft 18 and hence 5 causing levers 19 to rock, thereby shifting the shield or cover 15, as above described before the door proceeds toward open position to any considerable extent.

It will be noticed as shown, that when 10 the door is in its closed position the end 4 of the lever 3, is in a horizontal plane slightly lower than that of the shaft 9, and, therefore, the first portion of the motion of the lever 3 will have no tendency to open the 15 door and before the continued motion of the lever 3 initiates the movement of the door toward its open position the cam 10 will raise the lever 21, thereby pulling the shield or step covering against the side of the door 20 where it is held in place by the circular or concentric portion of the face of the cam 10.

When the door 12 is being closed the shield or step cover 15 will still be held against the side of the door by the action of 25 the circular or concentric portion of the cam 10 but when the door is fully in closed position, the final motion of the lever 3 will bring the flat face 11 of the cam 10 under the lever 21 whereupon spring 24 will pull 30 the lever 21 quickly down upon the face 11 of the cam and thereby throw the lower edge of the shield or cover 15 into its outward and downward position to form a step cover. If it is desired at any time to open 35 the door 12 without the shield or step cover 15, being operated, the latter may be retained in its folded position against the side of the door by any suitable catch device, as indicated at 25.

40 The shield or step cover 15 may also be operated by hand whenever required by simply rocking lever 21 against the action of the spring 24. The motor which operates the door may be controlled in any suitable 45 or convenient manner and, if desired, may be of any desired cushion type. I have shown a simple arrangement wherein the supply of pressure medium to and from the respective closed ends of the double cylinders is controlled through a control valve mechanism indicated generally at 40, and having a control or operating handle 41.

Having now set forth the objects and nature of my invention and a construction embodying the principles thereof, what I 55 claim as new and useful and of my own invention, and desire to secure by Letters Patent is:—

1. In a combined door and step cover, operating mechanism, a door, a step cover associated therewith, means for moving the door to open and closed position, and connections operated coincidently with the door moving means for shifting the cover 60 into and out of position to form a cover,

the step cover being moved out of cover position in advance of substantial movement of the door from its closed position.

2. In a combined door and step cover operating mechanism, a door, a step cover associated therewith, means for moving the door to open and closed position, and connections operated coincidently with the door moving means for shifting the cover into and out of position to form a cover, 70 the door actuating means operating to substantially complete the door closing movements before the step cover is shifted into position to form a cover for the steps.

3. The combination with a door and means for moving the same, of a step cover carried by the door, and connections operated by the door moving means for moving the cover against the door in advance of any substantial opening movement of said door. 80

4. The combination with a door and means for moving the same, of a step cover carried by the door, and connections operated by the door moving means for moving the cover against the door, said connections 90 operating in advance of any substantial door opening movement.

5. The combination with a door and means for moving the same, of a step cover carried by the door, and connections operated by the door moving means for moving the step cover into and out of position to form a cover for the steps, said connections operating to move the cover into position to form a step cover after the door substantially completes its movements in closing. 100

6. The combination with a door and means for moving the same, of a step cover having hinged connections with the door and means actuated by the door moving 105 means for rocking the step cover relatively to the door and into and out of position for use.

7. The combination with a door and means for moving the same, of a step cover having hinged connections with the door, and means actuated by the door moving means for rocking the cover relatively to the door into and out of position for use, said means operating in advance of the opening movement of the door to any appreciable extent to move the cover out of position for use. 110

8. The combination with a door and means for operating the same, of a step cover having hinged connections with the door, and means actuated by the door moving means for rocking the cover relatively to the door into and out of position for use, said means operating after the door has substantially completed its closing movement to move the cover into position for use. 120

9. The combination with a door and means for operating the same, of a step cover associated with the door, connections 125

130

operated by the door operating means for moving the step cover into and out of operative position, said connections permitting the independent manual operation of said cover.

10. The combination with a door and means for moving the same, of a step cover carried by the door and means actuated by the door moving means to cause the step 10 cover to be projected over the area to be covered or to lie up against the door.

11. The combination with a door and means for moving the same, of a step cover having hinged connection with the door, and 15 means actuated by the door moving means for projecting the cover over the area to be covered and to withdraw the same against the side of the door.

12. The combination with a door and 20 means for moving the same, of a step cover having hinged connection with the door, means actuated by the door moving means for projecting the cover over the area to be covered, and to withdraw the same against 25 the side of the door, said means serving to retain the cover against the door and out of position for use, during the door movements.

13. The combination with a door and means for moving the same, of a step cover 30 movably connected to the door, a member connected to the door to move therewith, means operated by the door moving means for moving said member relative to the door, and means operated by the movement of 35 said member relative to the door for shifting the step cover into and out of position for use.

14. The combination of a door, means for moving the same, a cam operated thereby, 40 a step cover movably connected to the door, and means operated by the cam for moving the cover into and out of position for use.

15. The combination of a door, means for 45 moving the same, a cam operated thereby, a lever actuated by the cam, a step cover movably connected to the door, and means op-

erated by said lever cam for moving the step cover into and out of position for use.

16. The combination of a door, means for 50 moving the same, a rotatable rod carried by the door, a step cover movably connected to the door, connections between the cover and rod whereby when the latter is rotated the cover is moved relative to the door into 55 and out of position for use, and means operated by the door moving means for rotatively moving said rod.

17. The combination of a door, means for 60 moving the same, an axially rotative rod connected to the door, a cam operated by the door moving means, devices actuated by the cam for axially rotating said rod, a step cover and connections between the step cover and rod for moving the cover into and out 65 of position for use.

18. The combination of a door, means for 70 moving the same, an axially rotative rod connected to the door, a cam operated by the door moving means, a lever arranged to be engaged and rocked by said cam, connections between said lever and rod whereby when the former is rocked the latter is axially rotated, a step cover carried by the door, and connections operated by the axial 75 rotative movement of the rod for moving the cover into and out of position for use.

19. The combination with a door and means for moving the same, of a step cover, 80 connections for operating the step cover, and means common to the door and cover operating means for controlling the same, the step cover being moved out of position for use in advance of any substantial opening movement of the door.

In testimony whereof I have hereunto set my hand in the presence of the subscribing witnesses, on this 26th day of October A. D., 1912.

HAROLD ROWNTREE.
